UNITED STATES PATENT OFFICE.

JOSEPH MUNDEN, OF DERRY TOWNSHIP, WESTMORELAND COUNTY, PENNSYLVANIA.

CARBURETER.

1,099,714.

Specification of Letters Patent.

Patented June 9, 1914.

Application filed March 22, 1913. Serial No. 756,254.

To all whom it may concern:

Be it known that I, JOSEPH MUNDEN, a citizen of the United States, residing at Derry township, in the county of Westmoreland and State of Pennsylvania, have invented certain new and useful Improvements in Carbureters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to internal combustion engines, but more particularly to a carbureting or mixing device for the proper vaporization of liquid fuel employed for operating the engine.

The invention has for its object to provide a carbureting or vaporizing device which can be used in connection with kerosene oil or the lighter distillates of crude oil, and which is equally efficient when used in connection with gasolene, alcohol and the like.

A further object of the invention is to provide a carbureting or vaporizing device which requires no heat supplying device to assist in the vaporization of the fuel.

A further object of the invention is to provide a carbureting or vaporizing device which is so constructed and arranged that no troublesome float feed regulator is required.

A further object of the invention is to provide a carbureting or vaporizing device which is so constructed and arranged that a sudden opening of the throttle will allow the engine to instantly respond by preventing an excess supply of fuel.

A further object of the invention is to provide a carbureting or vaporizing device which by reason of its construction and arrangement is less effected in its operation by weather or atmospheric changes than other carbureting or vaporizing devices now in use, and which by reason of its construction so thoroughly vaporizes the fuel as to render the starting of an engine easily accomplished in cold weather.

With these and other objects in view the invention consists in the novel construction of the carbureter body and in the novel construction of the needle valve sleeve.

The invention further consists in the novel arrangement of the air intake openings in the carbureter body and in the arrangement of a plurality of mixing chambers adjacent the needle valve sleeve.

The invention further consists in the arrangement of an air inlet chamber surrounding the needle valve and in the form and construction of the lower portion of the needle valve sleeve.

The invention further consists in the combination between the needle valve sleeve and the nipple forming the seat for the needle valve.

The invention further consists in the combination of the carbureter body construction and the air valve arranged between the needle valve and the engine.

The invention further consists in other novel details of construction and in combinations of parts, all of which will be first fully described and afterward specifically pointed out in the appended claims.

Referring to the accompanying drawing: the figure represents a vertical longitudinal sectional view of a carbureting or mixing device constructed in accordance with this invention, the air valve being shown in elevation.

Referring to the figure by reference numerals, 1 indicates the carbureting or vaporizing device which comprises a body portion 2, the said body portion being provided with a vertical bore or opening 3 in the upper portion of the body, said bore or opening 3 communicating with the enlarged bore or opening 4 in the lower portion of the carbureter-body. The upper portion of the smaller bore or passage 3 is threaded at 5 to receive a plug-like sleeve-element 6, which plug-like sleeve element is headed at 7 and internally threaded at 8 to receive the needle valve 9. The threaded passage 8 in the headed portion 7 communicates with an enlarged vertical chamber 10, which enlarged chamber terminates at the annular internal shoulder 11, the needle valve 9 passing vertically through the enlarged chamber 10 and through the restricted air passage 12 below the internal annular shoulder 11, as will be clearly apparent from the accompanying drawing. The plug-like sleeve element 6 is reduced in its external diameter at 13 to provide a relatively long annular chamber 14 between the reduced portion 13 and the surrounding wall 15 of the vertical

bore 3. The relatively small vertical bore 3 terminates at 16 at which point it opens into an enlarged mixing chamber 17, said mixing chamber 17 communicating with a plurality of horizontal air passages 18 extending from the mixing chamber 17 to the exterior surface of the carbureter-body.

As will appear from the accompanying drawing the needle valve 9 is provided near its lower end with a longitudinal gradual taper 19, while the extreme lower end of the valve is provided with a relatively blunt taper 20.

Referring now to the nipple 21 in the lower portion of the carbureter-body it will be seen that the same is provided with a preferably hexagonal enlargement 22 and is threaded at 23 to enter the enlarged threaded bore 4 in the carbureter-body, the hexagonal enlargement 22 bottoming snugly against the bottom surface of the carbureter-body to provide a fluid tight connection between the parts, while the lower portion of the nipple 21 is threaded at 24 to receive a suitable pipe connection leading to the fuel tank. Centrally of the nipple 21 is a vertical fuel bore 25 which terminates at its upper end in a tapered seat 26 to receive the tapered end of the needle-valve, in the manner which will be clearly apparent to those skilled in the art. That portion of the nipple 21 above the threaded portion 23 is reduced in its external diameter as at 27 and the casing or body portion 2 recessed 30 or undercut as at 26^a to such an extent as to form an air-chamber 28 and an upward annular extension 27^a of the chamber 28, said extension or passage communicating with the intermediate mixing chamber 17; while a horizontal air passage 29 in the carbureter-body effects communication between the annular air chamber 28 and the atmosphere, as will be apparent from an inspection of the accompanying drawing.

Referring now to the plug-like sleeve element 6 it will be seen that a suitable elastic packing 30 is employed under the headed portion 7 so as to permit of a suitable adjustment of the plug-like sleeve element in a vertical direction, while the needle valve 9 is provided with a knurled head 31 and a coil spring 32 which allows for a vertical adjustment of the needle valve and prevents the same from accidental rotation during the operation of the device.

Referring to the accompanying drawing it will be seen that the carbureter body comprises also a lateral extension 33 which is provided with a relatively large chamber 34 which communicates with the elongated annular air passage 14 by means of a horizontal air passage 35, said horizontal air passage 35 being reduced at 36, in the manner as shown in the accompanying drawing.

65 Suitably seated within the large mixing

or valve chamber 34 is a valve 37 preferably of the mushroom type having a stem 38 passing through a guiding boss 39 under the lateral extension 33, the stem being provided with a coil spring 40 in such manner that a suitable tension can be placed upon the valve 37, it being clearly understood that any suitable tensioning means can be employed in connection with the valve stem. 70

At the extreme end of the lateral extension 33 is a flange 41 for effecting a flanged connection between the carbureter and the engine or between the carbureter and the intake pipe leading to the engine, the position of the carbureter in relation to the engine 30 being entirely immaterial, while a horizontal passage 42 is provided through the flange 41 to allow the atomized or vaporized fuel to freely pass to the engine. 75

Referring now to the lower portion of the plug-like sleeve member 6, it will be seen that the extreme end thereof is slightly enlarged at 42', while the inner surface of the end of the member 6 is provided with an abrupt taper 43 and a relatively gradual taper 44 just above the abrupt taper 43, and it will be seen that the upper reduced portion 27 of the nipple 21 is provided with a flat surface 44' which is directly under the compound tapered end of the plug-like sleeve element 6, while a centrally extending boss 45 on the nipple 21 partially extends within the compound tapered end of the element 6 about midway the gradual taper. 90

As will be seen from an inspection of the accompanying drawing an open annular space 46 is provided between the lower extended end of the plug-like sleeve element 6 and the upper flat face 44 of the nipple 21, the size of said space 46 being regulated or 100 adjusted by means of the plug-like sleeve element 6; that is to say that movement in a vertical direction of the plug-like sleeve element 6 will increase or diminish the space 46 between the plug-like sleeve element 6 and the nipple 21 as will be apparent from 105 an inspection of the accompanying illustration. 110

Having thus fully described the several parts of this invention its operation is as 115 follows: The carbureting or vaporizing device is first suitably connected to an internal combustion engine and suitably piped to a fuel tank or receptacle which feeds to the carbureter by gravity or by pressure feed. 120 In either event the liquid fuel passes in through the fuel bore 25 in the nipple 21 and out at the top thereof when the needle valve 9 is in open position as shown in the accompanying drawing, the amount of fuel 125 being adjustable by means of the said valve as is obvious. Upon the intake or suction stroke of the engine the valve 37 raises, allowing the final mixture of proper explosive proportions of air and fuel to pass to the 130

engine cylinder, the engine suction drawing air from around the needle valve before it overcomes the tension upon the air valve in effecting the lifting thereof. The suction or pull of the engine cylinder causes air to pass in through the lower horizontal air passage 29 in the body portion and enter the annular air chamber 28 surrounding the reduced upper portion of the nipple 21. The air passes upwardly from the said chamber 28 into and through the passage 27^a and enters the mixing chamber 46 surrounding the lower flanged portion 42^a of the plug-like sleeve member 6. At the same time air is drawn into the obliquely arranged air passage 6' in the plug-like sleeve member 6 and passes downwardly into the air chamber 10 surrounding the needle valve 9 where it strikes against the shoulder 11 near the lower end of said member 6. The velocity of air is increased at this point owing to the relatively small passage 12 surrounding the tapered portion 19 of the needle valve 9. This construction causes air passing downwardly around the needle valve to be deflected against the tapered portion 19 of the needle valve and downwardly against the top surface of the boss 45 which forms the seat for the needle valve. As the air is passing downwardly and the fuel is being fed the high velocity and cutting motion which is given the air at this point causes it to mix and vaporize the fuel so that a perfect rich vaporization is effected. The vaporized fuel which is formed at the end of the needle valve is drawn out through the mixing chamber 17 between the nipple 21 and the lower end of the plug-like sleeve member 6 which is adjustable by means of the plug-like sleeve member 6 so that the velocity and amount of vaporized gas can be controlled at this point. As the gas leaves this space it is commingled with the air in the mixing chamber 17 which is drawn in through the air ports 18 and is also commingled with the air from the annular chamber 28 which is drawn in through the lower horizontal air passage 29. These different passages cause a cutting pulverizing movement of the air and when this air in its disturbed condition mixes with the rich vaporized gas a perfect mixture of air and gas is provided for in the mixing chamber 17 from whence it passes upwardly through the elongated annular air passage 14 and into the reduced portion 36 of the horizontal air passage 35. The velocity of the air at the point of mixture is so great and the air is in such a state of disturbance and perturbation that a perfect mixture and vaporization is effected. The gas thus drawn into the horizontal air passage 35 is again mixed in the chamber 34 with the air entering said chamber from the valve 37. Consequently as the

gas passes from the carburetor through the passage 42 it is in a state of perfect vaporization and the proportions of air to gas can be adjusted by means of the adjustments heretofore described so that the mixture 70 will quickly and readily ignite under and in all weather and atmospheric conditions, while at the same time the perfect vaporizing of the gas by means of this device causes the engine to operate with increased power 75 owing to the fact that the carburetion is so perfect that instant ignition is effected, while at the same time a saving of fuel is thereby effected.

Having thus fully described the invention 80 what I claim as new and desire to secure by Letters Patent of the United States is:—

1. A carbureter of the type described, including a casing or hollow member having a lateral chambered extension equipped 85 with a tensioned air-inlet valve, a fuel-feeding nipple member, a chambered or tubular plug and a needle-valve, said plug having its chamber provided with a contracted port and an air inlet, said casing and said plug 90 adapted to conjointly form an intermediate chamber, and upper and lower chambers communicating with said intermediate chamber, said upper chamber also communicating with the chamber of said lateral extension, said lower and intermediate chambers having external air-feeding passages, 95 said needle-valve controlling the contracted port of said plug, said port communicating with said intermediate chamber. 100

2. A carbureter of the type described, including a casing having a valved chambered extension, and a tubular or hollow plug having an air inlet to its interior and an upper end collar or shoulder resting upon said casing, said plug having adjustable or threaded connection with said casing, said plug having an annular recessed portion forming with said casing a chamber, said plug also having a lower end enlargement and at its 110 lower end a port of relatively reduced area and with a compound beveled surface adjacent a mixing chamber conjointly formed by enlarging said casing at the end of said plug, and a needle-valve arranged within 115 said plug and adapted to control said port. 105

3. A carbureter of the type described, including a casing having a lateral valved extension, a fuel feeding nipple fitted within said casing, a needle valve, said nipple having an upstanding boss around its fuel feeding bore, a tubular plug having an upper end air inlet and at its lower end a reduced bore surrounding said needle valve to produce a swift and centrally deflected air current, a portion of which is caused to strike on the end of said boss causing a crushing and outward glancing of the fuel thereon, another portion of said air current being caused to cut downwardly of the sides of 120 125 130

- 4
- said boss crosswise of the glancing fuel to finely cut and pulverize the same, said casting being enlarged and said plug being reduced to conjointly form chambers in communication with said reduced bore in said tubular plug, the external air and the chamber of said lateral flanged extension.
4. A carbureter of the type described, including a casing having a valved lateral chambered extension, a nipple having a fuel-feeding bore, and a threaded connection with said casing, said nipple having a reduced upper end uniting with said casing to form a chamber and an upwardly extending passage, said nipple having an upper end boss around its bore, a tubular plug having an air inlet and an internal shoulder at its lower end, and a port through said end, said plug forming in conjunction with said casing communicating mixing chambers, said chambers themselves communicating with said port and the chamber of said lateral extension, and a needle-valve arranged within said tubular plug and controlling said port.
5. In a carbureter of the type described, a casing having a valved lateral chambered extension, a nipple having a fuel feeding bore and an upstanding boss around its bore, a tubular plug fitted within said casing and having an air inlet, a relatively contracted port in its lower end, said lower end having a compound tapered or beveled lower surface, said casing and said plug conjointly forming triple chambers therebetween in communication with said port, the lower end of said plug being adapted to deliver the air received from the lower chamber crosswise of the mixture conjointly formed of the fuel received from said nipple and the air from the said relatively reduced port further pulverizing and mixing said mixture and means for the delivery of the final mixture in the proper explosive proportions to the motor.
6. In a carbureter of the type described, including a casing having a valved chambered lateral extension, a chambered plug fitting within said casing and having an upper shouldered end with an elastic packing between the shoulder and said casing, said tubular plug having an air-intake through its upper end communicating with its chamber, said chamber having its bottom formed by an internal annular shoulder, said bottom having a relatively contracted port therethrough, said bottom having a compound beveled or tapered lower surface, a nipple having a fuel-feeding bore and an upstanding boss at its upper end around its feeding bore, said casing, plug and nipple being reduced to conjointly form a triple series of communicating chambers, one communicating with the chamber of said chambered lateral extension, the intermediate one having passages communicating with the external air, and the third having a passage also communicating with the external air, said intermediate chamber having direct communication with said port through the passage-way formed by the compound beveled or tapered surface of the lower end of said plug, and a spring locked needle-valve having a compound tapered surface with its lower abrupt tapered end adapted to control said port.
- In testimony whereof, I affix my signature, in presence of two witnesses.

JOSEPH MUNDEN.
